FIG. 1

FIG. 5

FIG. 2

FIG. 3

FIG. 4

FIG. 1 is a front elevation view of a reflector showing my new design, the rear being substantially identical;
 FIG. 2 is a right side elevational view thereof;
 FIG. 3 is a top plan view thereof;

FIG. 4 is an enlarged fragmentary cross-sectional view taken along the line 4—4 of FIG. 1; and

FIG. 5 is an enlarged view of the portion of the lens indicated by circle 5 in FIG. 1, it being understood that the facets are continuous over the entire face of the lens.

The standard is broken away in FIG. 1 to indicate indeterminate length. The facets are omitted from the lens in FIG. 1 for convenience of illustration.

I claim:

The ornamental design for a reflector, as shown and described.
